DISPLAY CABINET

Joseph E. Gauvreau, Somerville, Mass., assignor
to E. F. Kemp, Inc., Somerville, Mass., a corpo-
ration of Massachusetts

Application May 1, 1939, Serial No. 271,163

3 Claims. (Cl. 312—114)

My invention relates to cabinets for use in displaying and dispensing merchandise, particularly confectionery, and it has for its object to provide an improved cabinet of this class.

5 It is also an object of this invention to provide an improved cabinet of the class indicated which will be particularly adapted for use upon a store counter; which can be produced at a minimum cost, and whose contents will not only be 10 attractively displayed to customers but can be conveniently and expeditiously dispensed and replenished.

To these ends I have provided an improved display cabinet having the features of construction and mode of operation set forth in the following description, the several novel features of the invention being separately pointed out and defined in the claims at the close thereof.

In the accompanying drawings:

20 Figure 1 is a front elevation of a display cabinet constructed in accordance with this invention.

Figure 2 is a rear elevation of the cabinet shown in Fig. 1.

25 Figure 3 is a section on line 3—3 of Fig. 2.

Figure 4 is a section on line 4—4 of Fig. 3 with the pan, hereinafter referred to, removed and with the prop member, also hereinafter referred to, in extended position.

30 The illustrated embodiment of my invention comprises a box-like housing made with a rearwardly inclined transparent front wall 10 of glass or the like; a bottom wall or transverse base member 11; two oppositely disposed side walls 35 12, 12, and a top wall 13. The bottom, side and top walls are fastened together in any suitable manner and are preferably made from wood, but any other suitable material may be employed in lieu thereof. The transparent pane of glass 10 is held in position by a sheet metal frame 14 that is fastened in any suitable manner to the bottom, top and side walls.

40 Pivottally connected by hinges 15 with the rear end of bottom wall 11 is a prop member or panel 45 16 which also may be made of wood, if desired, and by swinging said member 16 on hinges 15 it may be caused to occupy either the full line position shown in Fig. 3 or the dotted line position shown in said figure. When the prop member 50 16 is swung upwardly and forwardly from the dotted line position shown in Fig. 3 its movement in that direction is limited by the engagement of a pair of posts 17 carried by member 16 with the top side of the bottom wall 11, and when 55 said prop member occupies its full line position

with the stop posts 17 resting on top of bottom wall 11 said prop member is normal to the plane of the front transparent wall 10, as shown.

When the prop member 16 occupies the dotted line position shown in Fig. 3 a pan of confectionery 18 may be placed in position upon the bottom wall 11 and the posts 17 of prop member 16 as shown by dotted lines in Fig. 3. The pan 18 is made with a flange 19 adapted to rest upon the posts 17 and when the prop member is swung 10 upwardly and forwardly toward its full line position, Fig. 3, the pan 18 is swung pivotally upon its forward end into a position where it is parallel with the transparent front wall 10 as shown by full lines in Fig. 3. Upstanding abutment 15 posts 20 provided upon the bottom wall 11 adjacent to the transparent front wall 10 hold the lower end of the pan properly spaced away from the transparent front wall, while the upper end of the pan may, as shown, be wedged against the 20 top wall 13, thus when the prop member 16 occupies the full line position, shown in Fig. 3, it also is wedged into position against the pan and frictionally held in pan-holding position against accidental displacement. 25

Within the housing the two corners at the top thereof are filled in with corner blocks 21 having their exposed inner surfaces curved to conform with, and fit close to, the periphery of the flange 19 on pan 18. The width of the interior of the 30 housing closely approximates, but is slightly more than, the width of the pan. Thus flies and the like are excluded from the compartment existing between the pan 18 and the transparent front wall 10 when the pan is in position within 35 the housing. Also, the corners at the bottom of the interior of the housing between pan 18 and the transparent front wall 10 are filled in and closed by corner blocks 22 against which the lower marginal portion of the pan is pressed and 40 held by the prop member 16.

The free end of the prop member 16 is formed at its middle with a notch 23 which provides a finger-hole for use in manually swinging the prop member from its full line position, Fig. 3, 45 into its dotted line position.

What I claim is:

1. A display cabinet adapted to receive within it a removable pan of confectionery or the like that is to be displayed, said cabinet comprising a 50 housing made with an inclined transparent front wall, a top wall, two oppositely disposed side walls and a horizontal bottom wall, and a prop member pivotally connected at its one end with the rear end of said bottom wall, said prop member 55

being adjustable on said pivotal connection so as to occupy either a forwardly inclined position within said housing where it is disposed approximately perpendicularly with respect to the bottom of the pan and in endwise abutting engagement with said bottom so as to removably and directly support said pan in position within the cabinet and parallel with said transparent front wall, or so as to occupy a horizontal pan-supporting position at the rear of said bottom wall where it serves as an extension of the latter.

2. A display cabinet constructed in accordance with claim 1 wherein said housing is made in-

teriorly with abutments against which the pan or the like is removably clamped by said prop member so that it and its contents are held in a position parallel and out of contact with said transparent front wall.

3. A display cabinet constructed in accordance with claim 1 and wherein means is provided for limiting the forward swinging movement of said prop member so that when it is at the limit of its movement in that direction it is approximately 10° normal to the plane of said transparent front wall.

JOSEPH E. GAUVREAU.
